Specification for Design.

Patented May 31, 1921.

Application filed March 20, 1920. Serial No. 367,496. Term of patent 3½ years.

To all whom it may concern:

Be it known that I, OLE M. SVENDSEN, a citizen of the United States, residing in the city of Baltimore, State of Maryland, have invented a new, original, and ornamental Design for a Sifter-Top Can or Similar Receptacle, of which the following is a specification, reference being had to the accompanying drawing, forming a part thereof, wherein—

Figure 1 is a view in elevation of a sifter top can embodying my design,

Fig. 2 is a top plan view thereof, and

Fig. 3 is a section on line 3—3 of Fig. 1.

What I claim is:

The ornamental design for a sifter top can or similar receptacle, as shown.

OLE M. SVENDSEN.
